UNITED STATES PATENT OFFICE.

GEORGE H. WILSON, OF AUGUSTA, GEORGIA.

WARP STOP DEVICE.

1,377,045.

Specification of Letters Patent. Patented May 3, 1921.

Application filed May 13, 1920. Serial No. 381,072.

To all whom it may concern:

Be it known that I, GEORGE H. WILSON, a citizen of United States of America, residing at Augusta, in the county of Richmond and State of Georgia, have invented new and useful Improvements in Warp Stop Devices, of which the following is a specification.

The object of the invention is to provide a warp stop device for use with looms to be operated by specially prepared warp, such as that prepared on a slasher having the attachments shown in the applicant's co-pending application filed May 7, 1919 and bearing Serial No. 295,430. This specially prepared warp has gaps formed in its selvage edge at specified intervals and in the device herein shown, an attachment traverses the selvage edge and is operable upon its encountering a gap, the device being connected with means operating to throw a lever connected with the warp stop mechanism. It serves as a positive stop for the loom at specified intervals when the loom is running the specially prepared warp and may be employed without interference with the other automatic stops for the loom.

As herein shown and described, a specific embodiment of the invention is adhered to, but to such embodiment it is not to be restricted in so far as its limits may be prescribed by the appended claims.

In the accompanying drawings:—

Fig. 1 is a plan view of a portion of a warp beam running the specially prepared warp and showing the improved device operatively connected therewith.

Fig. 2 is an enlarged plan view of the device *per se*.

Fig. 3 is a front elevational view of the structure of Fig. 2, the supporting means therefor being shown in section.

Fig. 4 is a side elevational view of the structure of Fig. 2.

The warp (1) after having been prepared in the slasher to provide the gaps (2) at specified intervals along its selvage edge is transferred with the beam (3)—on which it was wound in the slasher—to the loom, a portion of the frame (4) of which is shown. The loom frame is provided with a transverse bar (5) disposed just ahead of the beam (3) and ahead of this bar there is positioned what is commonly known as a drop wire box (6), a lever (7) having its end entering this box for engagement by the device constituting the present invention.

The lever connects with and operates the stopping device for the loom which obviously may be of any preferred form, which, not being essential to the understanding of the invention, is not illustrated or described herein.

The automatic stopping device constituting the present invention is mounted on the transversely disposed bar (5), the warp passing from the beam over this bar and those threads which constitute the warp being engaged by the stopping device. The latter comprises an appropriate support consisting of a plate (8) formed with a horizontal U-shaped member (9), the upper leg of which is made longer than the lower leg so as to underlie the warp threads where they pass the same, as indicated at (10). This upper leg is formed with an opening (11) and with oppositely disposed up-turned ears (12) and (14), the latter being at the extremity of a lateral extension in which there is formed a slot 14^a communicating with the opening 11. An intermediate bearing support (15) is disposed between these ears. The plate (8) is secured on the bar (5) by means of a U-shaped clamp member (16) which embraces the bar and which is secured to the plate by means of appropriate bolts (17). The U-shaped member (8) is thus held in its proper position with respect to the passing warp. Obviously loosening the bolts (17) with the consequent loosening of the U-shaped member (16) from the bar (5) will permit adjustment of the plate and its attendant U-shaped member longitudinally along the bar thus providing for adjustment of the device when there is necessity of positioning it for operation with a particular warp.

Pivotedly supported in the ears (12) and (14) and in the bearing support (15) there is a rod (18) which is formed with a U-shaped portion (20) so disposed that it projects laterally from the rod member (18) and lies on top of the edge of the selvage threads of the passing warp (1).

One end of the rod member (18) is formed with an eye (22), to which there is connected a cord or flexible member (23) trained over a pulley (21) mounted on one wall of the box (6). The remaining end of the cord or flexible member is attached to a weight (24) which, when lowered, engages the lever (7) to operate the stopping device for the loom.

- The U-shaped portion (20) traverses the warp threads, the latter keeping it substantially horizontally disposed until a gap (2) in the passing warp is encountered. 5 The U-shaped portion will then drop by gravity and may pass in the slot 14^a) upon the application of a force in the direction of the length of the rod member (18). Such a force is provided by the weight (24) and 10 the rod member will therefore move longitudinally and the weight will be lowered, the latter dropping into the drop wire box (6) where it impacts with the lever (7) thus causing the latter to operate the loom stopping member. Thus when the warp thread is being worked on the loom, the latter is automatically stopped each time a gap (2) in the warp reaches the stopping device and the attendant knows that a cut mark has 15 20 been reached even though he be not present to see the cut mark or gap.

The invention having been described, what is claimed as new and useful is:—

1. The combination with a loom carrying a warp provided at predetermined points on the selvage edge with gaps, of a member movable through the gaps but playing upon and traversing those portions of the selvage threads between the gaps, and a loom stopping device operatively connected with said member and rendered operable upon movement of the latter through any one of the gaps. 25
2. The combination with a loom equipped with a warp stop operating device and carrying a warp prepared with gaps in its selvage edge, at predetermined points or a gravity actuated member traversing the said selvage edge and provided with means for 30 operative engagement with the warp stop device, the said member being movable through any of the said gaps.
3. The combination with a loom equipped with a warp stop operating device and carrying a warp prepared with gaps, at predetermined points, of a member traversing the warp and provided with means for operative engagement with said warp stop device, the said member being movable 35 through the gaps and actuatable upon encountering the same.
4. The combination with a loom equipped with a warp stop operating device and carrying a warp prepared at predetermined points with gaps, of a gravity actuated member traversing the warp in the path of the gaps and provided with means for operative engagement with the said warp stop operating device, the said member being 40 movable through the gaps and actuatable upon encountering any one of the same.
5. The combination with a loom equipped with a warp stop operating device and carrying a warp prepared with gaps in its selvage edge at predetermined points, of a 45 pivotally mounted gravity actuated member traversing the said selvage edge, the said member being movable through any of the said gaps and provided with means for operative engagement with said warp stop device.

with a warp stop operating device and carrying a warp prepared with gaps in its selvage edge at predetermined points, of a 65 pivotally mounted gravity actuated member traversing the said selvage edge, the said member being movable through any of the said gaps and provided with means for operative engagement with said warp stop device.

6. The combination with a loom for running a warp prepared with gaps in its selvage edge and having a warp stop device, of a rod member formed with a U-shaped 75 laterally projecting portion, means for pivotally mounting the said rod member so that the said U-shaped portion may bear on and traverse the selvage edge of the warp, and a gravity actuated member connected with the 80 rod member for operative engagement with the warp stop device, the said U-shaped portion being operable through any of the selvage edge gaps to impart pivotal movement to the rod member. 85

7. The combination with a loom for running a warp prepared with gaps in its selvage edge and having a warp stop mechanism, of a rod member formed with a laterally projecting U-shaped portion for bearing engagement upon the selvage edge, means pivotally supporting the rod, means for adjusting the last said means laterally with reference to the direction of movement of the warp to properly position the 95 U-shaped portion on the selvage edge, and a gravity actuated member engageable with the warp stop mechanism, the U-shaped portion being operable through any of the gaps to impart pivotal movement to said 100 rod.

8. The combination with a loom for running a warp prepared with gaps in its selvage edge and having a warp stop mechanism, of a rod member formed with a laterally projecting portion, a horizontally disposed U-shaped member having its upper leg formed with an opening and with ears pivotally supporting the rod member, the laterally projecting portion of the latter 105 being dimensioned to pass through said opening and being designed to traverse the selvage warp threads which pass between the said laterally projecting portion and the said upper leg of the U-shaped member, 110 and a gravity actuated device carried by the rod member for operative engagement with the warp stop mechanism, the laterally projecting portion being operable through said gaps to impart pivotal movement to the rod 115 member.

In testimony whereof I affix my signature.

GEORGE H. WILSON.
